(57) **CLAIM**

(21) Appl. No.: **29/245,230**

The ornamental design for an earpiece for a communications headset, as shown and described.

(22) Filed: **Dec. 19, 2005**

DESCRIPTION

(51) **LOC (8) Cl. 14-01**

This application is related to U.S. design patent application Ser. Nos. 29/245,216 and 29/245,231 both filed concurrently herewith.

(52) **U.S. Cl. D14/205**

FIG. 1 is an upper left front perspective view of an earpiece for a communications headset showing our new design;

(58) **Field of Classification Search** D14/188,

FIG. 2 is a front elevation view thereof;

D14/192, 205, 206, 223, 225, 226; 181/129,

FIG. 3 is a rear elevation view thereof;

181/130; 379/430, 433; 381/376, 377, 378,

FIG. 4 is a bottom plan view thereof;

381/379, 380, 381, 374; D24/173, 174

FIG. 5 is a top plan view thereof;

See application file for complete search history.

FIG. 6 is a right side elevation view thereof; and,

(56) **References Cited**

FIG. 7 is a left side elevation view thereof.

The ornamental design that is claimed is shown in solid lines

in the drawings. The broken line outline of a headset

microphone boom in the drawings is shown for environmental

purposes only, and forms no part of the claimed

design.
